SCISSORS HOLDER FOR APRONS

Alfred G. Johnson, Seattle, Wash.

Application November 22, 1941, Serial No. 420,141

1 Claim.

(Cl. 24—3)

This invention relates to workmen's aprons such, for example, as aprons adapted to be worn by paper-hangers.

An important object of my invention is to provide a workman's apron having in combination therewith a scissors holder located in out-of-the-way position and so constructed and arranged that the workman by a simple movement of his arm and without removing his eyes from the work he is performing can quickly and conveniently move the scissors into and out of the holder.

Another object of my invention is to provide a scissors holder of simple and inexpensive construction capable of being attached to a workman's apron, the holder having a spring clip for yieldingly retaining a pair of scissors in position to be readily grasped by the workman, and means for guiding the scissors into engagement with the clip.

Other objects and advantages will be apparent from the following detailed description of a preferred embodiment of my invention, reference being had to the annexed drawing in which:

Figure 1 shows an apron having a scissors holder attached thereto;

Figure 2 is a plan view of the scissors holder; and

Figure 3 is a side view of the scissors holder, taken on the line 3—3 of Figure 2.

Referring to the drawing, in Fig. 1 is illustrated a workman's apron 1 adapted to be worn by a paper-hanger and having a belt 2 and neck-band 3 adapted to encircle the waist and neck, respectively. The apron is preferably made of canvas or other durable flexible material, and to one side of the apron below the waist is attached a scissors holder 4 adapted to retain a pair of scissors 5, shown in dotted lines, in vertical position, pointed-end down.

As best illustrated in Figs. 2 and 3 the scissors holder 4 comprises a plate 6 of stiff metal bent into arcuate shape and conforming substantially to the drape of the apron along the side of the workman's body. Secured to this plate is a clip 7 of spring metal, this clip being bent into the form shown in Fig. 3 and comprising a terminal section 8 rigidly secured to the plate by means of rivets 9, an intermediate, outwardly offset scissor-supporting section 10, and a terminal tongue 11 bowed in a direction opposite to the curvature of the plate 6. The open end of the holder is directed toward the front of the apron and by reason of the divergent curvature of the tongue and plate a wide gap is formed there-

between which serves to guide the scissors into engagement with the clip. The forward end 6a of plate 6 also protects the apron against wear and damage which would result due to the repeated rubbing of the scissors against the fabric of the apron. In order to reinforce the apron in the locality in which the plate 6 is attached, a patch 12 of a heavy fabric is stitched to the apron, as best illustrated in Fig. 3.

As will be apparent from the foregoing description, when the apron 1 is worn, the scissors holder 4 will support a pair of scissors 5 in a position adapted to be conveniently grasped by the workman by moving his arm down to his side and engaging his fingers therewith. Then by moving the scissors laterally, the clip 7 is sprung outwardly to release the scissors. After use, the scissors are returned to the holder by moving them laterally into the gap between the tongue 11 and the plate 6 by which they are then guided beneath the clip, which yields to allow the scissors to snap into the scissor-supporting recess provided by the offset section 10.

The apron and scissors holder just described is especially useful for paper-hangers who, by the nature of their work, are required to make frequent and intermittent use of the shears in trimming wall paper to length. Ordinarily the scissors holder 4 will be affixed to the right-hand side of the apron; however, in the case of a left-hand workman, the holder will desirably be positioned on the left-hand side of the apron.

Manifestly various changes in structure and design may be made in the apron and scissors holder described above without departing from the spirit of my invention as defined in the following claim.

I claim:

A scissors holder adapted to be secure to workmen's aprons comprising a flat metal plate bent into arcuate shape throughout its length, an elongated single-piece, spring metal clip rigidly affixed at one end to said plate and at its other free end bearing against the plate by spring pressure, said clip being of substantially less width than the plate and formed with an intermediate offset portion of generally U-shape arranged to embrace a pair of scissors and the free end of said clip being curved in a direction opposite from the curvature of the plate so as to define therewith a relatively wide mouth for receiving and guiding the scissors laterally beneath the clip into the offset portion.
